ADJUSTABLE JIG

Henry N. Renton, Akron, Ohio, assignor to
Weather-Seal, Inc., Barberton, Ohio, a corpora-
tion of Ohio

Application June 14, 1944, Serial No. 540,275

7 Claims. (Cl. 144—292)

1

This invention relates to adjustable jigs or clamps, and more especially it relates to mitered clamps adapted to hold a plurality of work-pieces in determinate angular position while adjacent pieces are being secured to each other.

The invention is of especial utility in the manufacture of rectangular articles, for example, window sash or screen sash. In the most modern type of storm windows, interchangeable storm sash and screen sash are receivable in a supplemental frame that is permanently mounted in the window opening of a building. In order to exclude wind and weather, the storm window sash may have tongue and groove engagement with the supplemental frame, and for this reason an extremely nice interfitting of the parts is required to prevent binding, and to enable the storm sash readily to be mounted in or removed from the supplemental frame. Obviously the sash of the interchangeable screens require equally accurate construction for the same reason.

Heretofore the manufacture of sash with four mitered corners has been a relatively slow process. It required that the operator manually hold two sash elements together, after aligning them by visual observation, while a clamp was screwed up firmly to hold the pieces in position. The pieces were then drilled and screws inserted. This produced one corner of a sash, and the operation had to be repeated to produce the other corners of the sash. Since the four rail members of a sash require to be in the same plane, as well as positioned at exactly 90° angles at the corners, it will be apparent that inaccuracies were inevitable and frequent.

The chief objects of this invention are to produce window sash and screen sash of superior quality; to eliminate some of the manual operations in the manufacture of sash of the character mentioned; to provide apparatus for clamping together the four rails of a sash concurrently at the four corners of the latter; to provide apparatus of the character mentioned that is readily adjustable to accommodate sash of various sizes and proportions; and to save time and labor in the manufacture of sash and thereby to reduce the cost thereof. Other objects will be manifest as the description proceeds.

Of the accompanying drawings:

Fig. 1 is a side elevation of the improved adjustable jig, and the work thereon;

Fig. 2 is a plan view thereof;

Fig. 3 is a detail plan view, on a larger scale, of one corner portion of the apparatus, and work therein;

2

Fig. 4 is a section, on the same scale as Fig. 3, taken on the line 4—4 of Fig. 1;

Fig. 5 is a plan view, on a still larger scale, showing one of the work-engaging elements of the jig;

Fig. 6 is a section on the line 6—6 of Fig. 5;

Fig. 7 is a detail plan view, on a larger scale, of the operating mechanism at the center or axis of the jig;

Fig. 8 is a section substantially on the line 8—8 of Fig. 2 and Fig. 7;

Fig. 9 is a fragmentary detail plan view of the turntable of the jig showing how the same is latched in determinate angular position with relation to its base or supporting structure; and

Fig. 10 is a side elevation of the latching means shown in Fig. 9, the turntable and base being shown in section.

Referring to the drawings, especially Figs. 1 and 8 thereof, it will be seen that the apparatus comprises a base or supporting structure 10 having a flat top 11 of octagonal shape, said base and top being constructed of wood, although they may be made of metal if desired. Located at the center or vertical axis of symmetry of the top member 11 is an elongate sleeve 12 that is formed at its upper end with a radial flange 13, the latter being seated and secured in a suitable counterbore in the top 11 and the sleeve 12 extending downwardly through a suitable axial aperture in said top. Journaled in the sleeve 12 is a vertical spindle or axle 14 that has a circular disc-like hub 15 integrally formed on its upper end, said hub resting upon a thrust bearing 16 positioned between itself and the flange 13 of sleeve 12. Mounted upon the top side of the hub 15 and suitably secured thereto is a turntable 17 that consists of a flat metal plate and is square in plan. The turntable is marginally reinforced by an angle iron 18 welded thereto on the under side thereof, and also is reinforced by a second angle iron 19 attached to the under side thereof and arranged concentrically of the axis of the turntable.

The arrangement is such that the turntable may be rotated relatively of its supporting base 10, and means is provided for securing the turntable against rotation, in any one of eight different positions, so that operations may be performed upon work carried upon the turntable. To this end each corner of the turntable is provided, on the under side thereof, with a spring pressed latch engageable with one or the other of a pair of keeper members mounted upon the margin of the top 11, on two contiguous sides

of the latter. As is best shown in Figs. 9 and 10, each latch consists of an angular member 22 that is carried by a mounting block 23, the latter being secured to the under side of the turntable 17 at a corner thereof. The latch is slidably secured to the mounting block by a pair of cap screws 24 that extend through respective slots in the latch, the arrangement being such as to enable movement of the latch relatively of the block and diagonally of the turntable. A torsion spring 25 carried by the turntable engages the latch 22 and urges it inwardly, toward the axis of the turntable, the angular shape of the latch enabling it readily to be grasped by the operator's finger and drawn outwardly against the force of said spring. The nose of each latch 22, which is at the inner end thereof, is receivable in a notch 26 formed in the margin of a keeper member 27. There are two of the latter, and they are mounted on the margin of adjacent sides of the top 11. Each keeper member 27 consists of a metal strap that is bowed outwardly in its medial region so as to extend into the orbit of the nose portions of latches 22. The arrangement provides eight positions of angular adjustment of the turntable 17, of which one position is shown in full lines in Fig. 9 and another indicated in chain dotted lines in the same figure.

Secured upon the top of turntable 17, at the axis thereof, is the circular plate or base member 29 of an axial, upwardly extending stud or spindle 30, the latter being of largest diameter at its lower end, of intermediate diameter in its medial region, and of smallest diameter at its upper end portion, the latter being threaded. Rotatably journaled upon the spindle 30 and resting upon the shoulder formed at the top of its region of greatest diameter is a cam structure 31. A spacer disc 32 is superposed upon the cam structure 31, and a diametrically arranged two-hand crank 33 is superposed upon the disc 32, said crank, disc, and cam being secured together as a unit by a plurality of screws 34, and retained upon the spindle 30 by a nut 35 on the threaded upper end of the latter.

In plan, the cam 31 has the shape of a four-toothed ratchet, each of the four teeth or lobes of which has an arcuate camming face that terminates at a short, radial, non-camming face at the end thereof farthest from the axis of the cam. As is best shown in Fig. 8, the arcuate face of each lobe of the cam is formed with a downwardly extending flange 37 that is slidingly engaged in an upwardly open slot or notch 38 in an operating bar 39. There are four operating bars 39, and they are arranged diagonally of the square turntable 17, that is, radially toward the four corners of the latter. The radial extent of each cam lobe is substantially one-half inch, so that oscillation of the cam may be utilized to effect a maximum of one-half inch of longitudinal movement in each operating bar 39. Each of the latter has the shape of standard T-bar, the web or rib of which is uppermost, and includes the notch 38. The inner end portions of the respective bars 39 rest slidingly upon the upper face of the spindle-base 29, and are guided by respective pairs of guide rollers 40, 40 that are mounted upon the upper face of the spindle-base 29, and which engage opposite lateral faces of the upstanding webs of the operating bars. The outer end of each operating bar is formed with a loop or eye 41 that is utilized for adjustably connecting the bar to a threaded stud 42, the latter being mounted at one corner of a square metal

mounting plate 43. The latter are four in number, and they are positioned substantially coincident with the four corners of the turntable 17. Each mounting plate 43 is formed with a multiplicity of perforations 44, 44 that are arranged in rows parallel to the sides of the plate, the perforations being exactly equidistant from each other. The perforations 44 are somewhat tapered, their smaller ends being uppermost, at the top sides of the mounting plates.

The mounting plates 43 are arranged to be moved diagonally by longitudinal movement of the operating bars 39, and to this end each mounting plate has a key or gib 46 mounted on the bottom face thereof and secured thereto by screws 47, said gib being disposed diagonally of the mounting plate, in alignment with the operating bar 39 that is employed to move the plate. The gib 46 is formed in its opposite lateral faces with respective grooves 48, Fig. 3, that extend longitudinally from end to end thereof, and engaged in each groove 48 are complementally bevelled wheels or rollers 49, 49 that support the gib above the surface of the turntable 17. Each groove 48 of a gib is engaged by two wheels 49, the latter being disposed relatively near the opposite ends of the gib and the wheels on one side of the gib being disposed in opposition to the wheels on the opposite side thereof. Each wheel 49 is journaled in one end of a lever arm 50 that is pivotally mounted at 51 on the turntable 17. The other end of each lever arm 50 is engaged by an adjusting screw 52, the arrangement being such that the wheels 49 may be forced into operative engagement with the gib. The screws 52 that engage the lever arms 50 at the outer ends of the gibs are threaded through respective supporting plates 53 that are mounted upon the reinforced lateral margins of the turntable 17. The screws 52 that engage the lever arms at the inner end of the gibs are threaded through respective blocks 54 that are affixed to the top face of the turntable 17. The gibs 46 are formed with vertically arranged perforations 55, 55, Fig. 6, which perforations are in registry with perforations 44 in the respective mounting plates 43. The arrangement is such that the plates 43 operate unhindered by accumulations of dirt and sawdust in moving parts, it enables the plates to be positioned with micrometric nicety so that accurate work is produced, and it enables adjustment to be made to compensate for normal wear.

Mounted upon the mounting plates 43 are the four work-engaging units that engage the four mitered corners of a rectangular structure, such as a sash, and hold the sash elements fixedly in proper position while they are being secured to each other. In the drawings each work-engaging unit as a whole is designated by the numeral 58, and the respective work-pieces or sash rails are designated 59.

As is best shown in Figs. 4, 5, and 6, each work-engaging unit 58 comprises a five-sided metal block 61 that is so shaped as to have three right angles, said block having four sides that define said right angles, and having a fifth side that is disposed normal to a diagonal of the block. The bottom face of the block 61 is formed with a deep recess 62, Fig. 5, extending from said fifth side of the block to the right angle opposite the same, and mounted in said recess is a filler block 63 that occupies about half the recess at the end thereof that includes the right angle. The filler block 63 is secured in place by set screws 64.

Also mounted in recess 62, at the end thereof nearer the fifth side of the block 61, is a cramping block 65. Mounted upon the fifth side of block 61 is a cover plate 66 that covers the open end of recess 62, and a narrow slotted spacer plate 67, Fig. 6, is mounted in the latter between cover plate 66 and the adjacent end of cramping block 65. The length of said cramping block is such that it is capable of a modicum (about $\frac{1}{8}$ inch) of movement longitudinally of the recess 62, from and toward filler block 63, and for so moving said cramping block an adjusting screw 68 is threaded therethrough, the nose of said screw engaging said filler block. At its opposite end the screw 68 has a shank portion that extends through spacer plate 67 and cover plate 66, and has an operating knob 69 on the end thereof by means of which the screw is manipulated. Mounted upon the bottom of the block 61, at each side of the recess 62 and partly overlying the blocks 65, 63 therein are bottom plates such as the plate 70, Fig. 4. Secured to the top of the block 61 are two work-engaging members 71, 71 that are disposed exactly at right angles to each other. In transverse profile the members 71 are so shaped that they will engage the surface of the work-pieces 59 that rest thereon, and also will engage the lower part of the adjacent outer lateral face of said work-pieces, leaving sufficient of the latter exposed to receive the securing means, such as screws, that will hold said pieces together.

As shown herein, the four work-engaging units 58 are arranged to engage a work-structure in the shape of a square, but the apparatus is adaptable for operation upon work-structures of different rectangular shape, or on work-structures of the same shape but of different size. This feature of the apparatus is made possible by the ability of the units 58 to be mounted any place upon the respective mounting plates 43. To this end each unit 58 is attached to a mounting plate 43 by means of a plurality of studs or dowels 74, four dowels being employed for each unit. The dowels 74 are provided with tapered shanks, the large ends of which are slightly smaller than the small ends of the tapered perforations 44 in the mounting plates 43. The dowels 74 are permanently secured by any suitable means in respective bores or recesses formed in the bottom of a unit 58, there being two dowels mounted in the block 61, one dowel in the filler block 63, and one dowel in the cramping block 65, the tapered shanks of the dowels projecting below the unit. The perforations 44 being slightly larger in diameter (about $\frac{1}{8}$ inch) than the shanks of the dowels 74, enables the unit 58 easily and quickly to be mounted in position with the shanks of the dowels received in respective perforations 44. After the unit has been mounted as described, the operating knob 69 of screw 68 may be turned so that the latter moves cramping block 65 relatively of the remainder of the unit, with the result that the shanks of dowels 74 are urged or cramped against the tapered walls of the perforations 44 in which they are positioned, whereby the unit is retained firmly in position. The dowels 74 are easily released from the perforations 44 of the mounting plates 43 simply by manipulation of screw 68 and may be re-positioned in other perforations when it is desired to alter the jig to accommodate work of different size or rectangular shape.

After the jig has been set up to accommodate work-pieces of determinate size, its operation is

relatively simple and rapid. At the beginning of an operative cycle the hand crank 33 is turned to the position shown in full lines in Fig. 7, in which position the mounting plates 43 with work-engaging units 58 thereon are in their outermost positions. The four work-elements 59 are then placed in position with their end portions resting upon the members 71 of the units 58, after which the hand crank 33 is turned to the position shown in broken lines in Fig. 7. This rotates cam 31 and draws the bars 39 inwardly, and with them the mounting plates 43 and units 58 on the latter. Because the work-engaging members 71 of units 58 define exact 90 degree angles, and because said units are so arranged on the plates 43 that movement of the latter moves the members 71 in the direction of the bisectors of their angles, it will be apparent that said members 71 engage the end portions of work-elements 59 and force them into engagement with each other at the exact angle desired. While so held the mitered corners of the work elements may be drilled and secured to each other. The turntable 17 is latched in position while the work is being operated upon, but may be indexed to bring other corners of the work successively into position convenient for the operator. As shown in Fig. 6, the apertures 55 in the gibs 46 prevent the accumulation of shavings in perforations 44 underlaid by said gibs. As soon as all the corners of the work are secured together, the hand crank 33 is turned to the position shown in full lines in Fig. 7, thus releasing the finished work which may then be removed. This completes a cycle of operation.

An important feature of the invention is that no extraneous locking means is required to prevent retraction of the work-engaging units 58 after they have been drawn into operative engagement with the work. This advantage is achieved by so shaping the lobes of the cam 31 that their pitch is greatest in the respective regions thereof that are farthest from the axis of the cam. When the cam is fully turned to tightly engage the units 58 with the work, the operating bars 39 are nearly perpendicular to the camming surfaces of the cam lobes, with the result that the forces set up do not cause any recessive or reverse turning of the cam.

The invention is simple in construction and rapid and accurate in operation. It facilitates the output of work of superior quality, and achieves the other advantages set out in the foregoing statement of objects.

Modification may be resorted to without departing from the spirit of the invention or the scope thereof as defined by the appended claims.

What is claimed is:

1. In apparatus of the character described, the combination of a table, mounting plates positioned thereon each formed with multiple rows of perforations therethrough, angular work-engaging units each comprising a plurality of downwardly extending dowels that are receivable selectively in perforations in the respective mounting plates for operatively engaging the said units with the mounting plates, and means for effecting lateral movement of the dowels of each unit relatively of each other so as to cause said dowels to bind against the sides of the perforations in which they are seated.

2. A combination as defined in claim 1 wherein the perforations in the mounting plates are tapered with their smaller ends uppermost, and the dowels are similarly tapered, their larger ends

being slightly smaller than the smaller ends of the perforations.

3. A combination as defined in claim 1 wherein each work-engaging unit comprises two relatively movable elements, there being at least one dowel mounted in each element, and including an adjusting screw for moving said elements relatively of each other.

4. In apparatus of the character described, the combination of a table, a plurality of perforated mounting plates, means supporting said mounting plates on the table for determinate movement relatively thereof, said means comprising gibs secured to the under side of the respective mounting plates, each gib formed with longitudinally extending grooves in its lateral faces, wheels engaging each of said grooves, and adjustable supports on the table in which said wheels are journaled, work-engaging units mounted on the respective mounting plates 20 through the agency of said perforations, and means connected to the plates for concurrently moving them and the gibs relatively of the table.

5. A combination as defined in claim 4 in which the gib-engaging wheels are mounted in one end of respective lever arms, including adjusting screws engaging the opposite ends of said lever arms.

6. A combination as defined in claim 4 in which the gib-engaging wheels are arranged in pairs adjacent the respective ends of the gibs, the wheels on one side of the gibs being in opposition to the wheels on the opposite side thereof.

7. A combination as defined in claim 4 in which the gibs are formed with vertically disposed apertures that are in registry with a succession of perforations in the mounting plates.

HENRY N. RENTON.
